[57] **CLAIM**

The ornamental design for a combined air deflector and step for mounting below the front bumper of a truck, as shown and described.

DESCRIPTION

FIG. 1 is a perspective view of a combined air deflector and step for mounting below the front bumper of a truck showing our new design;

FIG. 2 is a front elevational view thereof on a reduced scale;

FIG. 3 is a top plan view thereof on a reduced scale;

FIG. 4 is a bottom plan view thereof on a reduced scale;

FIG. 5 is a right side elevational view thereof on a reduced scale;

FIG. 6 is a left side elevational view thereof, it being understood that the fragmentary broken line illustration of a front bumper and fender of a truck is for illustrative purposes only; and

FIG. 7 is a rear elevational view thereof on a reduced scale.
